UNITED STATES PATENT OFFICE.

KNUT JONAS ELIAS HESSELMAN, OF SALTSJO-STORANGEN, SWEDEN.

FUEL-SUPPLY PUMP.

Application filed September 26, 1922. Serial No. 590,720.

To all whom it may concern:

Be it known that I, KNUT JONAS ELIAS HESSELMAN, a citizen of the Kingdom of Sweden, residing at Saltsjo-Storangen, Sweden, have invented new and useful Improvements in Fuel-Supply Pumps, of which the following is a specification.

In the type of fuel supply pumps for internal combustion engines in which the plunger packing does not comprise a stuffing box but is realized by using an exceedingly accurate fitting of the plunger in its guide-way, it is of the utmost importance to prevent the plunger from exerting any pressure on the said guide-way due to lateral forces, as, otherwise, wear on the plunger with resulting leakage would easily occur.

In order to avoid said inconvenience it has been proposed to mount the plunger so as to permit it to move laterally relatively to its crosshead. In this way, however, the said inconvenience cannot be positively avoided, as friction will, of course, take place in the contact surfaces between the plunger and the crosshead, the latter having, furthermore, certain, though slight, lateral movements because of the fact that it is impossible to obtain an absolutely accurate fitting of the crosshead in its guide-way. A still further obstacle against the obtainment of the result desired is due to the fact that the said guide-way cannot be made mathematically parallel to the plunger guide-way.

This invention has for its object to provide means whereby any lateral force on the plunger is positively excluded.

The invention is characterized by the fact that a portion of the plunger situated between the plunger guide-way and the cross-head of the plunger is made elastic so as to be capable of yielding laterally in agreement with the play existing at the cross-head as well as in agreement with inaccuracies that might exist in the parallelism of the crosshead relatively to the plunger guide-way.

In the accompanying drawing a longitudinal section of a pump arrangement according to this invention is shown.

With reference to the drawing, the pump plunger 1 is operated by the cross-head 2

which is, in turn, driven by a cam 3 on the shaft 4. The plunger is mounted to snugly fit in the guide-way 5, and the cross-head is provided with a similar guide-way 6. A portion of the pump plunger is considerably reduced in diameter relatively to that of the plunger guide-way 5, as shown at 7, said portion having a convex head and being only dimensioned so as to satisfy the requirements as to resistance to lateral flexure and resistance to compressive stress while being capable of yielding laterally to such an extent as to compensate for the play that might exist at the cross-head, as stated above, as well as to compensate for inaccuracies that might exist as regards the parallelism between the guide-ways 5 and 6.

What I claim is:—

1. In a fuel pump for internal combustion engines, comprising a pump cylinder, a plunger member ground to fit exactly in said cylinder, a reciprocating cross-head member to drive said plunger, and a rigid guide for the cross-head, the combination with said ground-in plunger and said cross-head, of a laterally yielding rod rigidly connected to one member and having a convex head bearing loosely against the other member.

2. In a fuel pump for internal combustion engines, the combination with a pump cylinder, a plunger member ground to fit said cylinder, a reciprocating cross-head member and a rigid guide for the cross-head; of a laterally yielding rod rigidly connected to one of said members and having a convex head bearing loosely against the other member and a spring arranged to retract the plunger.

3. In a fuel pump for internal combustion engines, the combination with a pump cylinder, a plunger ground to fit said cylinder, a reciprocating cross-head and a stationary guide for said cross-head; of a yielding rod connected to said piston and having a convex head bearing loosely against the cross-head, and a coil spring surrounding said rod and operating against said head to retract said piston.

In testimony whereof I have signed my name.

KNUT JONAS ELIAS HESSELMAN.
